(57) **CLAIM**

The ornamental design for an exercise body bar, as shown and described.

DESCRIPTION

FIG. 1 is a first perspective view of an exercise body bar showing my new design;

FIG. 2 is a second perspective view thereof;

FIG. 3 is a third perspective view thereof;

FIG. 4 is a fourth perspective view thereof;

FIG. 5 is a front view thereof, the rear view being the same;

FIG. 6 is an alternative front view thereof with the vertical orientation of the exercise body bar being inverted, the rear view being the same;

FIG. 7 is a top plan view thereof;

FIG. 8 is a bottom plan view thereof; and,

FIG. 9 is a first end view thereof, the opposing end view being the same.

1 Claim, 4 Drawing Sheets
